(57) **CLAIM**

I claim the ornamental design for a reusable freezable plastic beverage cube, as shown and described.

DESCRIPTION

FIG. 1 is a perspective view of a reusable freezable plastic beverage cube according to an embodiment of the present invention.

FIG. 2 is a front elevation view of the reusable freezable plastic beverage cube of FIG. 1. The rear, left side and right side elevation views of the reusable freezable plastic beverage cube are identical to the front elevation view.

FIG. 3 is a bottom view of the reusable freezable plastic beverage cube of FIG. 1.

FIG. 4 is a top view of the reusable freezable plastic beverage cube of FIG. 1.

FIG. 5 illustrates the reusable freezable plastic beverage cube of FIG. 1 disposed in a beverage.

FIG. 6 is a perspective view of a reusable freezable plastic beverage cube according to another embodiment of the present invention.

FIG. 7 is a front elevation view of the reusable freezable plastic beverage cube of FIG. 6. The rear, left side and right side elevation views of the reusable freezable plastic beverage cube are identical to the front elevation view.

FIG. 8 is a bottom view of the reusable freezable plastic beverage cube of FIG. 6.

FIG. 9 is a top view of the reusable freezable plastic beverage cube of FIG. 6; and,

FIG. 10 illustrates the reusable freezable plastic beverage cube of FIG. 6 disposed in a beverage glass.

The broken lines and the entirely unshaded portions of reusable freezable plastic beverage cube illustrate portions of the reusable freezable plastic beverage cube and environmental structure that form no part of the claimed design.
